GAS ENGINE

Earnest M. Lindsey, Dayton, Ohio

Application September 26, 1939, Serial No. 296,629

14 Claims. (Cl. 123—56)

This invention relates to an internal combustion engine and more particularly to an internal combustion engine of the two-cycle type and adapted especially to the burning of a highly volatile hydrocarbon such as gasoline. The invention comprehends an engine embodying in combination a number of features cooperating to produce an engine developing more power per unit of weight than engines heretofore known, 5 an engine having longer life than previous engines, and an engine which is of less complex construction and more readily maintained in adjustment than the previously known engines.

It is an object of the present invention to provide a two-cycle engine having opposed power developing pistons connected together by a yoke, the pistons and connecting yoke moving in a straight line as distinguished from the conventional engine wherein the connecting rod is continually changing in direction; in this way the wear on the wrist pins is reduced to a practically negligible figure, and the sidewise thrust of the pistons upon the cylinders is eliminated.

Another object is to provide an engine of the type just described wherein the crank pin rotatably engages a crosshead, sliding within the yoke connecting the power developing pistons.

Still another object is to devise an engine of the foregoing type in which the yoke connecting the power pistons is also attached to pumping pistons operating within pumping cylinders disposed adjacent the power cylinders, the pumping pistons traveling in exact step with the power pistons fed by the pumping pistons.

Another object is to devise a valve mechanism preferably carried in a detachable valve head and which embodies only a single valve for the pumping cylinder, the intake valve for the power cylinder serving also as the exhaust valve for the pumping cylinder, whereby the number of valves required is reduced and the initial cost and the cost of maintenance of the engine are likewise reduced.

Still another object is to provide a timing gear which is rotatably journaled over the valve head and which is provided with circular cam surfaces engaging the respective valve stem ends; in a preferred form, each cam surface of the timing gear is provided with a plurality of valve operating surfaces, whereby the speed of rotation of the timing gear is reduced in proportion, and the wear on the timing gear on the cam surfaces therewith, and upon the timing gear operating mechanism is materially reduced, while at the same time the power required to operate the timing cam gear is also reduced.

Another object is to provide an engine having a timing gear which carries on one face thereof the cam surfaces arranged to actuate the valves, 60 these cam surfaces being formed integral with or

fixedly attached to the timing gear body, thus reducing the number of parts and eliminating the conventional cam shaft attached to the usual timing gear; the invention also provides for the elimination of the usual tappets or push rod mechanism for actuating the several valves, thus providing an engine of simpler construction, of more direct action, with less possibility for backlash and play, and with less wear and jar during prolonged operation. 10

Another object is to devise an engine of the foregoing type wherein the valves are capable of an extremely minute adjustment in a facile manner, so that they may be adjusted to substantially completely eliminate the usual clearance unavoidably present between the cam shaft and the ends of the valves. 15

Still another object is to devise an engine of the foregoing type wherein provision is made for the positive lubrication of all of the working parts, and in a preferred embodiment wherein an oil pump of improved design is employed for lubricating the motor.

Other objects of the invention will more fully appear as the detailed description thereof proceeds. 25

In the drawings:

Figure 1 is a plan view showing the general appearance of one form of motor embodying the principles of the present invention. 30

Figure 2 is a vertical transverse sectional view taken on the line 2—2 of Figure 1 at right angles to the crank shaft of the engine.

Figure 3 is a sectional view on the line 3—3 of Figure 2 showing the details of the connecting 35 sliding crosshead and yoke thereof.

Figure 4 is a vertical longitudinal section taken on the line 4—4 of Figure 1 and along the crank shaft of the engine.

Figure 5 is a detailed sectional view taken on 40 the line 5—5 of Figure 4 looking in the direction of the arrows. This view shows details of the oil pump assembly.

Figure 6 is a central vertical section through the valve head, timing gear and end of the combustion and pumping chambers of one end of the engine. 45

Fig. 7 is a sectional view on the line 7—7 of Figure 6 looking in the direction of the arrows.

Figure 8 is a section on the line 8—8 of Figure 6 looking in the direction of the arrows and shows the appearance of the cylinder head from the inner face thereof. 50

Figure 9 is a diagram showing the valve opening and closing sequence of the engine of the present invention. 55

Figure 10 is a sectional view taken on the line 10—10 of Figure 4 looking in the direction of the arrows.

Figure 11 is a detailed sectional view on the line 60

11-11 of Figure 10 and shows the sealing gasket arranged between the crank case end and the fill-in plate which carries the lower main bearing half.

5 Figure 12 is a section on the line 12-12 of Figure 8 and shows the location of the spark plug in the combustion cylinder head.

10 Figure 13 is a detailed horizontal section showing the timing shaft and its connection to the 10 valve operating timing gear at the outer end of the engine and to the gear mounted on the crank shaft which operates the timing shafts.

15 Figure 14 is an enlarged sectional view upon the line 14-14 of Figure 6 showing the details 15 of the valve construction and of the valve adjusting arrangement.

20 Figure 15 is a section on the line 15-15 of Figure 14 looking in the direction of the arrows and shows the means for obtaining an extremely 20 fine adjustment of the effective valve length.

25 Figure 16 is a plan view of the underside of the timing gear, showing the cam surface for actuating the valves.

30 Referring to the drawings in detail, and first 25 particularly to Figure 1, it will be observed that the engine illustrated is of the two cylinder horizontally opposed two-cycle type having a centrally disposed crank case designated generally as 1, the construction of which will more fully 30 appear below. The cylinder blocks 2 which are integral with crank case 1 project oppositely from this crank case and are of the air cooled type having the usual spaced air cooling fins. The valve heads designated generally as 3 are mounted upon the outward ends of the cylinder blocks

35 2. Housings 4 are mounted upon the outer faces of the valve heads 3 and serve to keep dirt and dust out of the valve operating mechanism as well as to provide a closed chamber for the circulation of oil over the valve mechanism. The 40 crank case 1 comprises a rearwardly extending flywheel housing 5 which is preferably integral with crank case 1 and which serves in cooperation with a cover member 6 to form an enclosed 45 flywheel chamber and a forwardly extending detachable fan housing 7 to the sides of which, as at 8, are attached air distributing hoods 9 adapted to lead the air from fan housing 7 outwardly and to then discharge it rearwardly over cylinder blocks 2 and the valve heads 3, thus effectively cooling the same. The air distributing hoods 9, it will be understood, are enlarged rearwardly to some extent, and are open at their rear portion so as to discharge the air rearwardly.

50 55 The propeller or drive shaft 10 is shown at the rear in Figure 1 and is directly connected to the crank shaft, or to the flywheel so as to be driven directly from the crank shaft of the engine. 11 indicates a pipe leading from a carburetor (not shown) and forming the initial portion of the intake manifold which is made up of two outwardly extending pipes 12 which carry the combustible gasoline-air mixture into appropriate intake ports 13 in the valve heads 3.

60 65 Referring now more particularly to Figure 2, the combustion cylinders are indicated at 14 and in them reciprocate the power pistons 15. Disposed just above power cylinders 15 are pumping cylinders 16 in which operate pumping pistons

70 75 17. Pumping pistons 17 are provided with wrist pins 18 pivotally engaged by one end of pumping connecting rods 19. Power pistons 15 have wrist pins 20 pivotally engaged by the outward ends of main connecting rods 21 which are considerably stronger than connecting rods 19 and which

converge toward the crank pin. These connecting rods 21 are integral at their inner ends with vertical slide rail members 22, reinforcing integral members 23 being preferably provided between members 22 and 21. The slide rail members 22 5 are connected at their upper and lower ends by means of curved channel-shaped yokes 24 so as to make a rigid slide frame for the sliding crank pin bearing. The inner faces of slide rail members 22 are concaved as at 25 (Figure 3) so as to 10 provide a sliding and aligning surface for the split crank pin bearing. The crank shaft 26 (Figure 4) comprises the usual main bearing portions 27, crank arm portion 28 and crank pin 29. The crank pin 29 rotates in a split bearing 15 30, the halves of which are carried on split members 31 which are made convex on their outer surface 32 to correspond with and be aligned by concave surface 25 of slide rail members 22. Crank pin bearing halves 31 are held together 20 by means of bolts 33 which are provided (Fig. 3) with a shoulder portion 34 at one end, with a threaded portion 35, and with polygonal sockets 36 at their other end adapted to be engaged by an Allen wrench, whereby the split halves may be 25 held together, threaded portion 35 threadably engaging a threaded opening in the bearing half 31. Each of the split halves 31 is provided with openings 37 to lighten the construction and to provide access to the bolts 33 for assembly and 30 disassembly.

The pumping piston connecting rods 19 are either pivotally or fixedly attached to the upper ends of slide rail members 22, as at 38. Thus, as the crank shaft 26 is rotated by the power 35 impulses upon pistons 15, the pumping pistons 17 are carried in step with power pistons 15 and the split crank pin bearing made of members 31 reciprocates vertically along slide rails 22, and in this way the slide rail assembly, connecting rods 21, and pistons 15 and 17 execute simple harmonic motion, instead of the approximation of simple harmonic motion obtained with the conventional connecting rod assembly. The wear upon wrist pins 20 and 18 is almost negligible 45 since there is substantially no oscillation of the connecting rods around the wrist pins. Likewise, the sidewise thrust of the usual connecting rods upon the pistons with resulting uneven wear upon the pistons and cylinders is completely eliminated. The construction of slide rails 22, and integral main connecting rods 21 coupled together by the yoke members 24, provides an assembly which is strong and sturdy but light.

An oil pan 39 (Figures 2 and 4) is detachably 55 secured to the lower portion of the crank case and serves as an oil reservoir for oil used in lubricating the engine. Figure 2 also illustrates the exhaust manifold 40 connected to the exhaust ports 41 of the valve heads 3.

The crank arm portion 28 of the crank shaft (Figures 3 and 4) is merely one portion of circular members 42 which are cast integral with the crank shaft and comprises heavy portion 43 (Figure 4) designed to counterbalance the crank pin 29.

60 65 Referring particularly to Figure 4, it will be seen that a cooling fan 45 is carried on a rotating member 46 keyed to the front end of crank shaft 26. The cooling fan is thus carried 70 inside of fan housing 7 and rotates at the same speed as the crank shaft 26. Preferably, fan 45 comprises eight large fan blades in order to prevent the motor from overheating. The usual crank indicated in dotted lines 47 may be provided 75

for manual cranking of the engine. Flywheel 48 is fixedly attached to the rear end of the crank shaft 26 in any suitable manner, and the flanged end 49 of driven shaft 10 is bolted to the crank shaft flange 50 by means of bolts 51 which pass through suitable holes in flywheel 48, thus boltting the three members 48, 49 and 50 together to rotate as a unit. Flywheel housing member 6 may be provided, if desired, with a tapered 10 roller bearing 52 for journaling driven shaft 10. Flywheel 48 may be toothed in the usual manner on its periphery for the engagement of the pinion 53 connected to a suitable starter.

Valve heads 3 are finned transversely as indicated in Figures 1, 2 and 6, the cooling fins on the valve heads being at right angles to the cooling fins on the cylinders 2, but the fins on the valve heads are adapted to have the air from the endmost portions of cooling hoods 9 pass over them in intimate contact with them. Where possible, as indicated at 54 in Figures 2 and 6, these cooling fins go all the way through valve heads 3, thus adding greatly to the cooling effect.

With particular reference now to Figures 6 to 8, it will be seen that the valve and cylinder heads 3 are attached to the cylinder blocks 2 by means of bolts 55, the usual gasket 56 being interposed therebetween. A combustion space 57 is provided over power piston 15 and within the valve and cylinder head 3. A compressing space 58 is likewise provided over pumping piston 11. An exhaust valve 59 adapted to allow exhaust gases to be discharged through exhaust port 41, and an intake valve 60 for combustion chamber 57 are provided. The spark plug is indicated at 61 (Fig. 12) and is located at the forward side of the domed combustion chamber in order to allow the combustion space 57 to be as small as possible.

The pumping cylinder 16 is provided with an intake valve 62 which is adapted to allow the combustible mixture to be sucked in from intake port 13. A passageway 63 leads from compressing space 58 to combustion cylinder inlet valve 60 whereby the compressed combustible mixture can be passed from the pumping cylinder into the combustion cylinder at the proper time.

Centrally disposed in the valve head 3 is an upstanding boss 64 into which is adapted to be fitted by shrinking a stubshaft 65 upon which is journaled by means of ball bearings 66 the timing gear 67 which is located within the housing 4, housing 4 being attached by bolts 68 to a plate 69 which is attached to a flange 70 on the valve head casting 3 as by bolts 71. The timing gear 67 is provided with peripheral teeth 72 which are enmeshed with a timing pinion 73 (Figure 13) fixedly mounted on timing shaft 74 which is driven by a beveled pinion 75 in turn driven by a bevel gear 76 fixedly mounted on crank shaft 26 (Figs. 4 and 13). A timing shaft housing 77 encloses the timing shaft 74 and is disposed between the crank case 1 and plate 69 in any suitable manner, bearings 78 of suitable type being provided for timing shaft 74. As will be apparent, timing gear 67 will be adjusted with reference to the motor and the valves so as to give the proper timing of the engine which will be discussed below. Timing gear 67 is held on stubshaft 65 by means of nut 79. Timing gear 67 is provided on its inward face with circular cam surfaces which are adapted to engage the ends of the three valves at each end of the motor 75 and to actuate the same in proper sequence so

as to cause proper operation of the motor. Timing gear 67 is rotated once every two revolutions of the crank shaft 26, and thus rotates at half the speed which would normally be imparted to the timing of a 2-cycle engine, and in this way 5 the wear on the timing gear and the drive therefor is materially reduced while at the same time the power required to drive it is also reduced. This reduction in speed of timing gear 67 necessitates that the cam surfaces thereupon be made 10 double so that each cam surface will actuate its valve twice during a revolution of timing gear 67.

Timing gear 67 is provided with a cam surface 80 for actuating the outer exhaust valve 59, with a cam surface 81 for actuating the inlet valve 15 60 to the combustion cylinder 14, and with a cam surface 82 for actuating the inlet valve 62 of the pumping cylinder 16. The usual valve springs 83 engaging shoulders 84 fixedly connected with the valves are provided for holding 20 the valves normally closed. The spring 83 of inlet valve 60 is sufficiently strong to prevent any leakage of gases compressed by piston 17 into power cylinder 14 prior to the opening of valve 60 by its cam track 81. The operation of the 25 engine and particularly of the valves thereof is illustrated in Figure 9 which portrays one complete cycle beginning with ignition in one end of the engine and ending with ignition in the same end of the engine. As the ignition impulse 30 takes place, both the intake and exhaust valves of the combustion cylinder 14 remain closed for one-fourth of a stroke. The pump valve 62 opens simultaneously with ignition, thereby allowing combustible gas to be drawn in 35 to the pumping cylinder 16 at the same time as a power impulse is generated in the power cylinder 14. The exhaust valve 59 of the power cylinder opens at the completion of one-fourth of a stroke, while the pump intake valve 62 remains open until the power and pumping pistons 40 have made one-half of a stroke. The pump intake valve 62 now closes while the power intake valve 60 remains closed and the exhaust valve 59 remains open. Upon the upstroke, the 45 pumping piston 11 compresses the combustible mixture thereabove to relatively high pressure until it is halfway towards the top on the upstroke. At this point, the exhaust valve 59 is closed and the power inlet valve 60 is opened, 50 allowing the highly compressed mixture above the pumping piston 11 to be discharged into the power cylinder under higher pressure than it would normally be. The pistons continue to move together until they reach the top of the upstroke, whereupon the intake valve 60 closes, 55 substantially all of the combustible gas above piston 11 having been pumped into the space above power piston 15 under relatively high pressure, and the continued upward movement 60 of piston 15 having served to further compress the combustible mixture above it. The parts are now in position for another cycle which is repeated in the same manner.

The ignition details other than the spark plugs 65 61 have not been indicated since they are conventional and form no part of the present invention. The ignition breaker may suitably be disposed within the fan wheel 46 and is so timed as to deliver a firing electrical impulse to the 70 spark plug 61 at the top dead center position of each cylinder at each revolution thereof.

There will now be described the lubricating system of the engine shown in the drawings. Referring to Figure 4, it will be seen that an oil 75

pump designated generally as 85 is provided having a closed casing 86 extending down below the surface of the oil. The shaft 87 of the oil pump is driven by a fixedly mounted bevel pinion 88 enmeshing with the same gear 76 which drives the valve timing mechanism. The portion of housing 86 which extends below the surface of the oil is provided with a downwardly open cuplike plate 89 over the lower open end of which is a screen 90. Plate 89 is provided substantially centrally with a hole 91 through which the oil is adapted to be sucked upwardly into the housing 86 by means of slanting vanes 92 of the impeller 93 fixedly mounted on the lower end of oil pump shaft 87. The shaft 87 is provided with a central bore 94 fluid connected to the supply of oil under pressure in casing 86 by means of diverging bores 95. It will be seen that as the impeller 93 is rotated in the proper direction, it will cause oil to be sucked up through hole 91 and to be forced under pressure upwardly through bore 94. Bore 94 communicates with a bore 97 in the lower half 96 of the main bearing of the crankshaft. Bore 97 communicates with a bore 98 in crank shaft 26, this bore 98 communicating with a bore 99 which lubricates the crank pin bearing 30. Suitable means is provided for allowing oil to escape from crank pin bearing 30 to lubricate the bearing surface 32 formed between concave surface 25 and convex surface 32. The oil continues under pressure along the bore 98 to a bore 99 which lubricates the front main bearing 100 which is provided with a fluid pressure take off as at 101 making fluid pressure connection with T-shaped member 102 to which are attached transversely extending valve head lubricating lines 103 (Fig. 1) entering the compartment 104 which serves as an oil chamber for oiling the valves and the timing gear 67. The oil leaves the compartment 104 through gravity return line 105 which conveys it to the oil pan 39 (Fig. 2).

Figure 10 illustrates the manner in which the rear main bearing is supported, the upper half 107 being carried fixedly in the crank case 1 in a suitable manner. The lower half 96 is carried fixedly at the upper portion of a plate 108 which is inserted in the side of the crank case 1 in any suitable manner, being gasketed by means of fibrous gasket material 109 laid in grooves 110 formed in the adjacent edges of the contacting surfaces. The two bearing halves 96 and 107 may be rigidly bolted together by means of bolts 111, thereby transferring a good deal of the load of the crank shaft to the crank case 1. Plate 108 suitably carries by means of a lug 113 the oil pump 85, and the extreme upper portion of oil pump shaft 87 may be journaled as at 114 in the lower main bearing half 96. Oil passing along the rear main bearing portion of the crank shaft may be received by a groove 115 and pass thence downwardly through a bore 116 to lubricate the bevel pinion 88 which in turn lubricates bevel gear 76 and thereby lubricates bevel pinion 75 of the timing mechanism.

I prefer to use a valve constructed as shown in detail in Figures 14 and 15. The valve is made in two main parts, the main stem 117 being threadably received within the portion 118 which is adapted to engage the valve guides. Cylindrical portion 118 is preferably provided with a piston ring 119 which is adapted to prevent leakage of gas or oil between the valve and the valve guide and is also provided with the outwardly extending portion 120 adapted to slidably engage the cam surfaces of the timing gear 67. The stem

portion 117 is enlarged as at 121 to form a firm support for the valve upon cylindrical member 118, a shim 122 of suitable thickness being interposed between enlarged portion 121 and the cylindrical portion 118.

To adjust the effective length of the valve, I provide enlarged portion 123 with transverse bores 124, and slot the threaded end of the valve stem as at 125. A locking pin 126 is provided which is adapted to pass through any one of bores 124 and through slot 125 thereby holding the stem 117 against rotative movement with respect to cylinder portion 118. By providing a plurality of radial bores 124, I am enabled to get an exceedingly fine adjustment of the effective length of the valve. For example, by providing eight radial bores 124, it is possible to adjust the valve length in increments equal to one-eighth of the thread pitch of the threaded engagement between members 117 and 118. In order to maintain a firm interconnection between 121 and 118 in the adjusted position, a new shim 122 of proper thickness is inserted to take up the new clearance. In practice, a series of shims 122 of varying thickness will be provided to facilitate this adjustment during maintenance or overhaul of the engine, only that shim of proper thickness being used and the remaining shims being held as a reserve.

Figure 16 shows in bottom plan view the timing gear 67 and illustrates how the cam ribs 80, 81 and 82 are formed with high points of the proper length to actuate the cams in accordance with the timing sequence of Figure 9. The exhaust valve operating rib 80 is provided with a high surface 127 and a corresponding high surface 128 located 180° therefrom, so that the exhaust valve 59 is alternatively opened by high points 127 and 128 which successively contact the same. High points 127 and 128 are each extended for one-fourth of the circumference of the rib 80, or for 90°. Similarly, pump valve operating rib 82 is provided with high points 129 and 130 for actuating the pump valve 62, each of these high points 129 and 130 extending for one-fourth of the circumference of the circle, or 90°, and these high points 129 and 130 are similarly arranged in series so as to successively open pump valve 62. Likewise, rib 81 for actuating the inlet valve 60 of the combustion cylinder 14 is provided with two high points 131 and 132, each of which extends for one-eighth of the circumference of the rib 81, or for 45°. The high points of ribs 80, 81 and 82 are arranged so as to carry out the valve operating sequence of Figure 9.

From the foregoing, it will be seen that the present invention provides an engine which is adapted to the development of great power per unit of weight by reason of the operation of the pumping pistons which feed the adjacent combustion cylinders. It will be seen that by the use of the sliding cross-head and the elimination of the oscillation of the connecting rods that I have provided an engine which is adapted to develop more horse power by reason of the elimination of friction and unnecessary thrusts. It will further be seen that the provision of the improved timing mechanism for the engine of the foregoing type still further results in increasing the effective power of the engine and eliminating to a large extent the maintenance costs of the previously employed engines.

I wish it to be understood that I desire to include as within my invention such modifications as may be necessary to adapt the same to varying

conditions and uses and as fall within the terms and spirit of the appended claims.

Having thus fully described my invention, what I claim as new and desire to secure by Letters Patent is:

5. 1. In an internal combustion engine, a combustion cylinder, a power piston therein, a pumping cylinder disposed alongside said combustion cylinder, a pumping piston in said pumping cylinder and arranged to travel in unison with said power piston, means for admitting a combustible gaseous mixture to said pumping cylinder as said pistons move on their downstroke and for exhausting spent gas from said combustion cylinder 10 for at least one half of said stroke, means for preventing said gaseous mixture from escaping from said pumping cylinder when said pistons move on their upstroke and for continuing exhausting said gas for at least one-half of said 15 stroke, and means for transferring the compressed gaseous mixture from said pumping cylinder to said combustion cylinder as said pistons pass the half-way point in their upstroke to continue compression of said gas by both pistons during the 20 final portion of said stroke.
25. 2. In an internal combustion engine, a combustion cylinder, a power piston therein, a pumping cylinder disposed alongside said combustion cylinder, a pumping piston in said pumping cylinder and arranged to travel in unison with said power piston, means for admitting a combustible gaseous mixture to said pumping cylinder as said pumping piston moves on its downstroke and for preventing said gaseous mixture from escaping 30 as said pumping piston moves on its upstroke, and means for transferring the compressed gaseous mixture from said pumping cylinder to said combustion cylinder as said pistons pass the halfway point in their upstroke and for preventing the 35 return flow of the gaseous mixture so transferred after they reach the end of their upstroke and begin on the downstroke.
40. 3. In a two-stroke-cycle internal combustion engine, a combustion cylinder, a power piston therein, a pumping cylinder parallel to said combustion cylinder and terminating substantially equally therewith, a pumping piston in said pumping cylinder, means for moving said pistons in their respective cylinders simultaneously and in step with one another, a passageway connecting the compression spaces of said cylinders, an inlet valve for said pumping cylinder, a common valve in said passageway serving as an outlet valve for said pumping cylinder and as an intake valve for 45 said combustion cylinder, an exhaust valve for said combustion cylinder, said valves being so timed with respect to said pistons that as said pistons begin their downstroke said inlet valve is opened and said common valve closed whereby 50 said pumping piston sucks in a charge of gas on its downstroke, that as said pistons pass the half-way point in their downstroke said exhaust valve is opened, that as said pistons reach the bottom of their downstroke and begin their upstroke said inlet valve is closed while said common valve remains closed, whereby said pumping piston compresses said charge, that as said pistons pass the 55 halfway point in their upstroke said common valve is opened and said exhaust valve is closed while 60 said inlet valve remains closed whereby the charge compressed by said pumping piston is transferred to said combustion cylinder during the last half of the upstroke, and that as said pistons complete the upstroke said common valve is closed to prevent 65 return of said charge.

4. In a two-stroke-cycle internal combustion engine, a combustion cylinder, a power piston therein, a pumping cylinder therefor disposed parallel thereto and having its termination substantially commensurate therewith, a pumping 5 piston in said pumping cylinder adapted to compress a charge of combustible gas and to deliver a charge so compressed to said combustion cylinder under pressure greater than said combustion cylinder would normally build up, connecting rods 10 for said pistons, a cross member connecting said connecting rods adapted to reciprocate transversely therewith but to remain stationary longitudinally, a crankshaft having a crankpin, and means interconnecting said crankpin and said 15 cross member for transmitting the transverse component of movement of said crankpin to said cross member to cause transverse reciprocation thereof while allowing said crank pin free movement along said cross member and substantially 20 preventing the right angle component of movement of said crankpin from being transferred to said cross member.

5. In a two-stroke-cycle internal combustion engine, a combustion cylinder, a power piston, a 25 pumping cylinder therefor disposed parallel thereto and terminating substantially therewith, a pumping piston therein, connecting rods for said pistons, a crankshaft having a crankpin, a cross-member, means connecting said crankpin 30 with said cross-member for causing said cross-member to be reciprocated by said crankpin but for allowing said crankpin to move freely along said cross-member, and means connecting one of said connecting rods to said cross-member for 35 preventing relative motion between said cross-member and said connecting rod, the other of said connecting rods being secured to said cross-member in such manner that the piston thereof is caused to reciprocate simultaneously with the 40 other piston, whereby relative movement of said connecting rods with respect to said pistons is eliminated.

6. In a two-stroke-cycle internal combustion engine, a pair of opposed combustion cylinders, 45 power pistons therein, a pair of opposed pumping cylinders, one of which is parallel to and cooperates with each of said combustion cylinders, a pair of pumping pistons, one of which is in each of said pumping cylinders and is adapted to compress a gaseous charge and deliver it to its combustion cylinder, said pumping pistons and said power pistons moving in step and in unison with each other, a crankshaft, a crankpin thereof, a centrally disposed yoke comprising two parts retained in parallelism, said operating power and pumping pistons being connected to opposite parallel parts of said yoke, a crankpin bearing disposed on said crankpin and within said yoke in such manner that it is 50 free to slide therein in a direction at right angles to said cylinders and pistons, but is fixed therein against transverse and parallel movement to said cylinders, said power pistons moving said yoke reciprocally in parallel and planar alignment therewith while said crank pin bearing moves at right angles to said plane whereby rotary movement is imparted to said crank pin.

7. In a two-stroke-cycle internal combustion 70 engine, a combustion cylinder, a power piston therein, a pumping cylinder parallel thereto, a pumping piston therein operating in step with said power piston, a common cylinder head for said cylinders, an inlet valve in said head for 75

said pumping cylinder, intake and exhaust valves in said head for said combustion cylinder, a transfer passageway in said head connecting said cylinders and valved by said intake valve, and a 5 cam member rotating about an axis parallel to the axes of said valves and timed with respect to the movement of said pistons for operating said valves.

8. In a two-stroke-cycle internal combustion 10 engine, a combustion cylinder, a power piston therein, a pumping cylinder parallel thereto, a pumping piston therein operating in step with said power piston, a common cylinder head for said cylinders, an inlet valve in said head for 15 said pumping cylinder, intake and exhaust valves in said head for said combustion cylinder, a transfer passageway in said head connecting said cylinders and valved by said intake valve, said valves having actuating stems extending parallelly outwardly, and a rotatable cam member journaled about an axis parallel to the axes of said valves and timed with respect to the movement of said pistons for operating said valves, said cam member having circular cam surfaces 20 on its inward face which are adapted to engage with the outward ends of said stems.

9. In a two-stroke-cycle internal combustion engine, a combustion cylinder, a power piston therein, a pumping cylinder parallel thereto, a 30 pumping piston therein operating in step with said power piston, a common cylinder head for said cylinders, an inlet valve in said head for said pumping cylinder, intake and exhaust valves in said head for said combustion cylinder, a transfer passageway in said head connecting said cylinders and valved by said intake valve, said valves having actuating stems extending parallelly outwardly, and a rotatable cam member journaled about an axis parallel to the axes of 35 said valves and timed with respect to the movement of said pistons for operating said valves, said cam member having circular cam surfaces on its inward face which are adapted to engage with the outward ends of said stems and rotating once every two full cycles of the power cylinder and provided with two full series-arranged cam surfaces for each of said valves.

10. In a two-stroke-cycle internal combustion engine, a combustion cylinder, a power piston 50 therein, a pumping cylinder parallel thereto, a pumping piston therein operating in step with said power piston, a common cylinder head for said cylinders, an inlet valve in said head for said pumping cylinder, intake and exhaust valves in said head for said combustion cylinder, a transfer passageway in said head connecting said cylinders and valved by said intake valve, said valves having actuating stems extending parallelly outwardly, and a rotatable cam member journaled 55 about an axis parallel to the axes of said valves and timed with respect to the movement of said pistons for operating said valves, said cam member having circular cam surfaces on its inward face which are adapted to engage with the outward ends of said stems, and rotating once for a plurality of full cycles of the combustion cylinder and provided with the same number of full cam surfaces arranged in series for each of said valves.

70 11. In an internal combustion engine, a combustion cylinder, a power piston therein, a pump-

ing cylinder, a pumping piston therein, said pumping cylinder and piston being adapted to draw in a combustible gaseous mixture and to compress the same, a fluid lubricating circuit for said engine, a valve head positioned upon 5 said combustion and said pumping cylinders, valve means within said head for controlling the flow of a combustible mixture through said cylinders, cam means positioned within said head and associated with said valve means for timing 10 the operations of said valve means, and means for connecting said valve head within the fluid lubricating circuit for said engine to cause lubricant from the engine to flow through said valve head.

12. In an internal combustion engine, a combustion cylinder, a power piston therein, a pumping cylinder, a pumping piston therein, said pumping cylinder and piston being adapted to draw in a combustible gaseous mixture and to 15 compress the same, a fluid lubricating circuit for said engine, a valve head positioned upon said combustion and said pumping cylinders, valve means within said head for controlling the flow of a combustible mixture through said cylinders, a cam member rotating about an axis parallel to the axes of said valves for timing the operation 20 of said valve means, and means for connecting said valve head within the fluid lubricating circuit for said engine to cause lubricant from the engine to flow through said valve head.

13. In an internal combustion engine, a combustion cylinder, a power piston therein, a pumping cylinder, a pumping piston therein, said pumping cylinder and piston being adapted to 35 draw in a combustible gaseous mixture and to compress the same, a fluid lubricating circuit for said engine, a valve head positioned upon said combustion and said pumping cylinders, valve means within said head for controlling the flow 40 of a combustible mixture through said cylinders, a rotatable cam means positioned within said head and interconnected with said valve means for timing the operation of said valve means, means drivingly engaging said timing cam and 45 positioned within said valve head, means interconnecting said time cam driving means with said engine, and means for connecting said valve head within the fluid lubricating circuit for said engine to cause lubricant from the engine to flow 50 through said valve head and lubricate said timing cam and driving means therefor.

14. In a two-stroke-cycle internal combustion engine, a combustion cylinder, a power piston therein, a pumping cylinder parallel thereto, a 55 pumping piston therein operating in step with said power piston, a fluid lubricating circuit for said engine, a common cylinder head for said cylinders, an inlet valve in said head for said pumping cylinder, intake and exhaust valves in 60 said head for said combustion cylinder, a transfer passageway in said head connecting said cylinders and valved by said intake valve, a cam member rotating about an axis parallel to the axes 65 of said valves and timed with respect to the movement of said pistons for operating said valves and means for connecting said cylinder head within the fluid lubricating circuit for said engine to cause lubricant from the engine to flow there-through.

70 EARNEST M. LINDSEY.
